UNITED STATES PATENT OFFICE

RUDOLPH L. SCHWARTZ AND WILLIAM PAUL MARTIN, OF BUFFALO, NEW YORK

DESIGN FOR A GASOLINE-PUMP CASING

Application filed February 6, 1929. Serial No. 29,965. Term of patent 14 years.

To all whom it may concern:

Be it known that we, RUDOLPH L. SCHWARTZ and WILLIAM PAUL MARTIN, citizens of the United States of America, residing at Buffalo, in the county of Erie and State of New York, have invented a new, original, and ornamental Design for a Gasoline-Pump Casing, of which the following is a specification, reference being had to the accompanying drawings, forming a part thereof.

Figure 1 is a side view of the article, Figure 2 is an end view showing our new design.

We claim:—

The ornamental design for a gasoline pump casing as shown.

RUDOLPH L. SCHWARTZ.
WILLIAM PAUL MARTIN.
